HEALD OF LOOMS FOR WEAVING

Mark William Carr, Keighley, England

Application March 6, 1935, Serial No. 9,604
In Great Britain March 28, 1934

9 Claims. (Cl. 139—92)

This invention relates to the type or class of healds for weaving which are usually styled "metal healds" and which require mounting or arranging in rectangular frames for securing the 5 healds in their operating positions, and my said invention has especial reference to the construction of the frame referred to, and by the provision and application of means whereby said frames are strengthened, more freedom is given 10 to the movements of the metal healds mounted thereon, and less liability of the healds causing defects in the weaving operations is encountered.

These features are secured according to my 15 invention by the employment of additional metal or other supporting bars, preferably mounted within the rectangular frame and of novel arrangement and formation for attachment to the usual wooden staves, so that upon said bars I may mount supporting members which are formed to afford all the desired support for the 20 well known metal bars or strips upon and over which the metal healds are looped or mounted. The said mounting of the metal bars upon which the healds are placed, also permits the supporting members to move freely longitudinally over 25 my added supporting bars which are secured to both the upper and lower staves of the rectangular frame, thus affording freedom for the movement of the healds to prevent same from exerting undue lateral strains upon the threads of 30 warp as they are when firmly and rigidly held under the ordinary conditions.

In the following description reference is made 35 to the accompanying sheet of drawings, which forms part of this specification, in which:—

Fig. 1 is a front elevation of a heald frame and a few healds shown mounted thereon as is hereinafter explained.

Fig. 2 is a sectional end elevation showing the 40 upper half of a heald frame and three horizontal bars which support the healds by the addition of intervening members.

Fig. 3 is a front elevation of one of the 45 wooden staves forming the rectangular frame and the ordinary metal bars which support the metal healds in the usual manner, and to these are added my additional longitudinal bar for supporting the other metal bars and their healds.

Fig. 4 is an end elevation showing my added 50 metal supporting bar and one of my improved members mounted thereon, the same being drawn to an enlarged scale.

Fig. 5 is a similar view to Fig. 3 but illustrates 55 a modification hereinafter described.

Fig. 6 is a front elevation similar to Figs. 3

and 5 and is intended to show the method in which my novel devices act when in use.

Fig. 7 is an end elevation similar to Fig. 4 but shows a modification hereinafter described.

Fig. 8 is a sectional elevation showing one of the supporting devices which I make use of according to my invention to afford an advantageous movement of the healds.

Fig. 9 is a perspective view showing a portion of one of my added bars of modified form, as 10 hereinafter described.

To attain the object of my invention I mount two additional bars 2, preferably of metal, (for use in broad looms, although they may be of wood when found to be advantageous) within 15 each of the usual and well known types of rectangular frames (comprising the wooden bars a , a^1 and their end binding members x , x^1 , Fig. 1) within which the healds 5 are mounted, and each of these additional bars 2, according to one formation, is of T-shape in cross section, the upper 20 one being in an inverted T position upon the upper wooden bar a , while upon the lower bar a^1 the bar 2 is in its upright T position.

The bar 2 of the shape described has its body 25 part b of appropriate thickness and of sufficient width or depth to fit snugly into a longitudinal groove c made lengthwise in the body of the bars a and a^1 so that the central portion of its body part b may be free to slide for a short space in a 30 vertical direction to permit any bending movements of the bars a and a^1 as they are moved by their operating cords apart from each other without moving the bars 2 to put greater longitudinal strains upon the healds 5. Each bar 2 35 has its lateral flanges b^1 and b^2 extending from it so that supporting members 3 may be mounted thereon in such manner that they are free to slide longitudinally over the said flanges b^1 and b^2 of said bar 2. The bar 2 is fixed near its 40 outer ends by cross pins d , d^1 which pass through the bar a and also through the bar a^1 .

The cross pins d , d^1 retain the ends of the bars 2 rigidly within their grooves in the wooden staves or bars a , a^1 in which they are situated. 45 However, by the springing or yielding of each of said bars or staves a , a^1 at about its central part as stated, being permitted without such movement being imparted to its bar 2 (by reason of its middle part between the pins d , d^1 being 50 loosely mounted in its groove in the bar a or a^1) sufficient freedom for the actions of the ordinary longitudinal bars aa^1 is allowed without causing same rigidly to bind and hold its bar 2 against all relative movement therewith. By 55

these means only such a longitudinal pull is put upon the healds 5 by their operating bars 4 as will adequately operate said healds 5 and their threads of warp without causing the engaging 5 looped ends of said healds 5 upon their bars 4 to be so firmly held as not to be bound thereon to prevent all lateral movement of same, but under such conditions as allow the said healds 5 sufficient freedom to move either to the right 10 or to the left of their normal positions to prevent them from forcing their warp threads into such rigidly confined positions as will cause abrasions on said threads.

To prevent the bar 2 from being moved too far 15 out of its groove c in its wooden stave a or a¹, a looped strip of metal 6 is fixed to the sides of the bar a or a¹ and has its looped part 6a bent through the opening 2d in the bar 2 in order that the edge 2c of the bar 2 may be arrested when 20 the looped formation 6a of the bar 2 reaches the end of its path.

Mounted to extend over the flanges b¹ and b² of each of the bars 2 are the supporting members 3 which are of a bifurcated formation, so that 25 their outer ends may be turned inwardly and terminate in a curved formation 3a shown by Fig. 8 to rest upon the flanges b¹, b² of the bar 2 in order that when any of the healds 5 are caused, by the lateral pull of the warp threads upon them, to 30 move longitudinally over their supporting bars 4, the acting of said healds 5 upon the ends 3a of the members 3, secures the desired slipping movement to relieve the heald 5 of any resisting force that will retain it rigid and firm against 35 the actions of the threads of warp upon it, as hereinbefore stated.

The lower hooked ends 3b of the supporting members 3 are to receive and support or be supported by the bars 4 upon which the healds 5 are 40 mounted.

As means for further facilitating the lateral movements of the members 3, the ends 3a may have mounted upon them balls or runners 7 which will run over the flanges b¹ and b² on the 45 bars 2 so as to afford less resistance to the lateral forces of the threads of warp upon healds adjacent to them because of the more easy running of the balls or runners 7 over the surfaces of the flanges b¹ and b² when arranged as is shown by 50 Figs. 5 and 7.

As a modification in the construction of the bars 2, the flanges b¹, b² may be bent towards each other to produce the tubular formation b⁵ shown by Fig. 9.

55 In this arrangement the supporting members 3 have their ends 3d formed to fit in the tube b⁵ in order to rest upon the edges b⁶ of the tube to be supported by same as they may move along the slot between them.

60 Although the tubular member b⁵ is shown with a web b⁷ extending from it, this may be dispensed with in cases (such as healds for narrow looms) where its tubular shape is found to be strong enough.

65 Such being the nature and object of my invention, what I claim is:—

1. A harness frame for looms, comprising a rectangular frame formed by grooved longitudinal bars being bound to each other by end 70 members at right angles thereto, metal healds, two horizontal metal bars upon which the healds are mounted, coupling elements detachably secured to the metal bars which carry the healds, additional bars connected by the elements on 75 the heald supporting bars, means for fixing the

outer ends of the additional bars in the grooves of the longitudinal bars of the frame, and means for limiting the movements of the longitudinal bars with respect to the additional bars.

2. A harness frame for looms, comprising a rectangular frame, longitudinal bars bound to each other by end members at right angles thereto, additional bars secured to the longitudinal bars, elements for securing the additional bars to the longitudinal bars to allow for any movement of the central part of the longitudinal bars from the additional bars, means for limiting said movement, heald carrying bars, hooked engaging members for coupling the additional and the heald-carrying bars to each other in their respective pairs, and metal healds having loops on their extremities fitting over the bars which carry them.

3. A harness frame for looms comprising spaced longitudinal bars having slots in their inner opposed edges, rail forming bars arranged in said slots and secured near their ends only to the longitudinal bars to allow for flexure of the central portion of the longitudinal bars, said rail forming bars being capable of limited vertical movement with respect to the longitudinal bars, heald supporting bars, healds carried thereby, and loosely sliding members receiving and supporting the heald supporting bars and supported by the rail forming bars.

4. A harness frame for looms comprising spaced longitudinal bars, each bar being slotted in its inner edge, a rail forming bar arranged in the slot of each longitudinal bar and secured near its ends only to the respective longitudinal bar to allow flexure of the central portion of the longitudinal bar, the inner edge of each rail forming bar being flanged and spaced from the inner edge of the respective longitudinal bar, heald supporting bars, healds carried thereby, coupling members mounted for loose slidable engagement with the flanges of the rail forming bars, the inner ends of said coupling members being formed with hooks for engagement with the heald supporting bars.

5. A harness frame for looms comprising spaced longitudinal bars, said bars being slotted at their inner edges, a rail forming bar fitted in the slot of each bar, transverse pins extending through the end portions only of the longitudinal bars and the rail bars to allow for flexure of the central portion of the longitudinal bars, means for limiting transverse sliding movement of the rail forming bars with respect to the longitudinal frame bars, heald supporting bars, healds carried thereby, and means for connecting the heald supporting bars to the respective rail forming bars in a manner as to permit longitudinal movement of the heald supporting bars with respect to the rail forming bars.

6. A harness frame for looms, comprising upper and lower longitudinal frame members formed with grooves in their inner opposed faces, rail forming bars having their body portions arranged in the grooves and secured only at their ends to the longitudinal members to allow for the flexure of the central portion of the longitudinal members, each rail forming bar having flanges formed on the inner longitudinal edge thereof, upper and lower heald supporting bars, healds mounted upon the supporting bars, and connecting members formed to engage loosely with the flanges of the rail forming bars and with the heald supporting bars.

7. A harness frame for looms, comprising a rectangular frame including longitudinal bars coupled together by end members at right angles thereto, additional bars secured to said longitudinal bars only near the ends thereof to allow for flexure of the central portion of the longitudinal bars and having lateral flanges formed upon them, heald supporting bars, connecting members, each having a pair of hooked engaging members at one end for spanning the additional bars and resting in contact with the lateral flanges thereon, while another hook is formed at the other end of said connecting members to engage with the heald supporting bars, and metal healds mounted between said supporting bars to be operated by them.

8. A harness frame for looms, comprising a rectangular frame, including slotted longitudinal bars, additional bars mounted in the slots of the longitudinal bars of the frame and secured thereto only near the ends thereof to allow for flexure of the central portion of the longitudinal bars, said additional bars having lateral flanges

on their inner longitudinal edges, coupling members having means at one end for loose slideable engagement with the lateral flanges, heald operating bars, hooks formed on the coupling members for supporting the heald operating bars, and healds mounted upon said heald operating bars.

9. A harness frame for looms, comprising a rectangular frame, including slotted longitudinal bars, additional bars mounted in the slotted longitudinal bars of the frame and secured thereto only near the ends thereof to allow for flexure of the central portion of the longitudinal bars, said additional bars having a slotted tubular track, heald supporting bars, supporting members having their outer ends constructed to operate in the tubular track and to rest upon and be supported by the inwardly curved edges of the same, with their outer ends to engage the heald supporting bars, and metal healds mounted upon said heald supporting bars.
